TO EDWIN B. STIMPSON COMPANY, OF BROOKLYN, NEW YORK, A CORPORATION OF
NEW YORK

FEEDING MECHANISM FOR RIVETING MACHINES

Application filed July 25, 1923. Serial No. 653,655.

This invention relates generally to the construction of improved feeding mechanism for riveting machines.

Feeding mechanism for riveting machines as heretofore constructed has not been wholly satisfactory in that there has existed a marked tendency for the parts either to become jammed or to fail to deliver rivets in unbroken sequential order. In either case the 10 operation of the machine was interfered with and in many cases the mechanism was broken and the efficiency of operation seriously restricted.

It is a general object of the present invention to obviate the objectionable features referred to and to provide a rivet feeding device which will operate with a minimum amount of jamming and which will automatically release or set free the very occasional blocks or jams which may occur.

The invention includes a feeding cup or cylinder having a radially slotted edge of a known character and rotatable about a horizontal axis to impel rivets one at a time 25 into a channel or runway leading to the point of attachment to the work by the riveting members. A feature of the invention resides in the means for supplying rivets to the feeding cup which includes a delivery orifice so arranged that the cup is maintained in only a partially filled condition which facilitates the arrangement of rivets in the radial slots and greatly decreases the tendency to jam.

Another feature of the invention resides 35 in the provision of step-by-step operating mechanism for rotating the feeding cup, the operating mechanism including a yielding ratchet actuating pawl which will slip out of engagement with a ratchet tooth in case of a jam and on the return stroke actuate the cup to release the jammed rivet.

Other features of the invention will be hereafter referred to.

45 In the drawings, in which a preferred form of the invention has been selected for illustration,

Figure 1 is a view in front elevation of a rivet feeding device embodying a preferred 50 form of the invention.

Figure 2 is a view in vertical section of the device taken at right angles to Figure 1.

Figure 3 is a view in rear elevation of the device shown in Figure 1.

Figure 4 is a view in front elevation of a 55 feed plate forming part of the device.

Figure 5 is a view in vertical section taken on the line 5—5 of Figure 4.

Referring to the drawings for a more detailed description of the invention, a rivet 60 feeding device is shown in which there is included a hopper 10 of any desired conformation and size and a chute 11 leading downwardly from the delivery orifice of the hopper and terminating at an orifice 12 in a feed plate 13 which closes an open side of the chute 11. At 14 is shown a feeding cylinder or cup having a radially slotted edge 15, the slots 16 of which are of a suitable size to receive the stem portions 17 of the rivets 65 which are fed through the device into suitable riveting mechanism not herein shown.

The feeding cup 14 is mounted to rotate with a shaft 18 which extends through the feed plate 13 and the chute 11 and is provided at the right-hand, as viewed in Figure 2 of the drawings, with a toothed ratchet pinion 19 through which step-by-step rotation is transmitted to the feeding cup.

75 The orifice 12 in the feed plate 13 is arranged to discharge into the lower portion of the chamber 20 provided by the cup. It will be seen that by this arrangement, the level of the mass of rivets delivered through the orifice 12 is maintained the level of the upper edge of the orifice. The relatively small mass of rivets thereby supplied to the feed cup only partially fills the chamber provided by the cup and thereby facilitates stirring and tumbling of the mass of rivets contained therein to insure that rivets will find their way 80 into the radial slots 16 as the slots pass beneath the mass of rivets adjacent the orifice 12.

85 The inner edge 21 of the feeding cup 14 is spaced from the adjacent edge 22 of the lower portion of the feed plate 13 adjacent the orifice 12 by a suitable distance to loosely receive therein the head portions 23 of the rivets as is clearly shown in Figure 2 of the 90 100

drawings. The channel thus provided by the spacing of the face 22 of the plate 13 from the edge 21 of the cup 14 extends in an arcuate formation along the lower portion of the plate adjacent the orifice 12 and leads into a channel 24 through which rivets are delivered in a counter-clockwise direction of rotation of the cup 14, as viewed in Figure 1, to find their way downwardly to the riveting mechanism 10 that is provided.

In order to prevent jamming of rivets that may for any reason be carried past the channel 24 the upper portion of the feed plate 13 is spaced at a relatively considerable distance 15 from the edge 21 of the cup 14 to provide a chamber or enlarged channel 25 through which the rivets may fall from their places in the radial slots 16 to again take their place as part of the mass of rivets in the lower portion 20 of the cup. As a further addition in the prevention of a jamming action the channel 24 is enlarged as at 26 into a widened channel 27 which extends around the upper half of the periphery of the cup member 14. It will be 25 seen that the enlarged channel 27 aids in the removal of rivets from the radial slots 21.

In order to rotate the feeding cup 14 the toothed pinion 19 is actuated by means of a driving pawl 28 which is pivotally mounted 30 on the upper end of an oscillating arm 29 driven in any suitable manner through an operative connection with the adjacent riveting machine.

In order to prevent breakage of the mechanism by the occasional jamming or catching of a rivet in such a way as to prevent rotation of the cup 14, the operating pawl 28 is 35 yieldingly held in operative position by means of a leaf spring 30 extending along the top of the pawl from its point of attachment to the upper end of the oscillating arm 29. By this arrangement the pawl 28 is permitted to slip out of engagement with a tooth 40 on the ratchet pinion 19 when increased resistance to rotation of the pinion is encountered by the presence of a jammed rivet. The slipping of the pawl 28 out of its engagement with the tooth will prevent breakage of the operating parts as will be clear and, in addition, 45 the return movement of the pawl along the curved face of the tooth has a marked tendency to reverse the direction of rotation of the cup and thereby release the jammed rivet so that on the next operating movement 50 of the pawl the step-by-step rotation of the cup can be resumed.

The feeding cup 14 is easily removed from its position on the drive shaft 18 to which it is fitted through a tapering connection 60 against which the cup is forced through a thumb nut 31 acting through a suitable spring member 32.

In the operation of the device rivets are supplied to the hopper 10 and find their way 65 through chute 11 to the orifice 12 through

which they are delivered in a restricted but constant supply to the interior of the feeding cup 14. In the step-by-step rotation of the cup 14 the rivets are tumbled and rolled about so that they find their way into the radial slots 16 in the edge of the cup and are thereby carried to the entrance end of the chute or channel 24 through which they are delivered to the riveting mechanism. The restricted delivery of the rivets to the interior of the cup 14 combined with the yielding step-by-step operation of the feed cup obviates jamming of the mechanism and insures a continuous successive delivery of rivets to the point where they are attached to the work. 70 75 80

In addition to the yielding function provided by the spring-held pawl member 28, the spring member 32 which is engaged by the thumb nut 31 may yield to permit the slipping of the feeding cup 14 on its shaft to thereby prevent injury to the mechanism when the parts are jammed. 85

What we claim is:—

1. In a rivet feeding device, a chambered rivet positioning member rotatable about a horizontal axis, and a vertically positioned expanding channel for delivering rivets into the positioning member. 90

2. In a rivet feeding device, a chambered rivet positioning member rotatable about a horizontal axis, a rivet supplying device having a delivery orifice opening laterally into the lower portion of said chambered member, and an expanding chute communicating with said orifice. 95 100

3. In an article feeding device, a chambered article delivering member rotatable about a horizontal axis, an article supplying device having a delivery orifice opening laterally into the lower portion of said chamber, an expanding chute leading to said orifice, and a delivery channel into which articles are fed by said rotatable chambered member. 105

4. In a rivet feeding device, a rotatable chambered rivet positioning member, means for intermittently rotating said member, said means including a ratchet and pawl mechanism, a spring normally holding the pawl against the ratchet and the relation of the pawl to the ratchet being such that the pawl will move against the pressure of the spring and move over a ratchet tooth without operating the same when the parts are jammed, said pawl operating to vibrate the ratchet and release the jammed parts on its return movement. 110 115 120

5. In a rivet feeding device, a chambered rivet positioning member rotatable about a horizontal axis, a vertical rivet supplying chute, a plate forming one wall of the chute, and having an orifice therein positioned to deliver rivets from the chute into the lower part of the chambered member, means for intermittently rotating the chambered mem- 125 130

ber, said means including a ratchet and pawl mechanism and a spring normally holding the pawl in yielding engagement with the ratchet, and said plate being spaced from the upper portion of the chambered member to release rivets carried into the upper portion of the member.

6. In a rivet feeding device, a chambered rotatable rivet delivering member, said member having open slots on its peripheral edge, a casing having a chute to deliver rivets to the lower part of said member, means carried by said casing to support said member on a substantially horizontal axis, said casing adjacent the upper portion of said member being provided with a recess to permit rivets carried upwardly by said slots to drop to the lower portion of said member, and means to intermittently rotate said member.

26 In testimony whereof we affix our signatures.

EDWIN B. STIMPSON.
JOSEPH F. SUESSLE.
